UNITED STATES PATENT OFFICE.

GEORGE CROSSLAND, OF AMSTERDAM, NEW YORK, ASSIGNOR TO MOHAWK CARPET MILLS, INC., OF AMSTERDAM, NEW YORK, A CORPORATION OF NEW YORK.

LOOM REED.

Application filed November 12, 1924. Serial No. 749,528.

To all whom it may concern:

Be it known that I, GEORGE CROSSLAND, a citizen of the United States, residing at Amsterdam, county of Montgomery, State 5 of New York, have invented certain new and useful Improvements in Loom Reeds, of which the following is a specification.

The present invention relates to reeds and more particularly to reeds for pile fabric 10 looms such as Axminster looms.

The reeds most commonly used at the present time have a retaining wire disposed near the top and at the rear of the reed for the purpose of preventing the warp threads 15 from jumping out of the spaces or slots between adjacent dents. This wire is supported by two spaced posts secured to the base of the reed. The arrangement is such that the wire prevents the warp threads 20 from moving into the topmost portion of said slots or spaces, with the result that the warp threads or ground fabric is some distance from the top of the reed even when said threads occupy the highest positions 25 they can assume. The knife that cuts the tufts travel in a plane inclined slightly to the horizontal and substantially tangent to the top of the reed. By reason of the fact that the warp threads, even in the highest 30 position, are removed considerably from the top of the reed, the knife cannot cut the tufts very close to the warp threads or ground fabric.

It is one of the principal aims of the present invention to provide a reed constructed 35 so that the knife can cut the tufts much closer to the ground fabric than heretofore.

Other objects of the invention are to provide an improved form of dent and improved means for supporting the retaining wire.

To these ends, the dents of the present invention comprise single straight bars shaped at their lower ends to fit in recesses in the 45 base of the reed and at their upper ends so that the slots or spaces between adjacent dents will be restricted to prevent lateral displacement of the warp threads when they occupy these spaces. Intermediate its end 50 portions each dent is rounded in cross section so that no sharp edges are presented to cut or injure the warp threads in their vertical movements. Two or more of the dents are provided at their upper rear corners 55 with ears that support the retaining wire.

The tops of the dents are shaped, and the ears are so located, that the path of the cutting knife is much closer to the warp threads, when in their highest positions, than heretofore. Furthermore, the wire is supported so that the warp threads may be moved substantially to the very tops of the slots or spaces between adjacent dents.

These and other objects will be apparent from the description taken in connection 60 with the drawings in which—

Figure 1 is a front elevation of a portion of the reed constructed in accordance with the present invention;

Figure 2 is a vertical sectional elevation 70 of the reed;

Figure 3 is a horizontal sectional view through a dent taken substantially on the line 3—3 of Figure 2;

Figure 4 is a horizontal sectional view 75 through a dent taken substantially on the line 4—4 of Figure 2;

Figure 5 is a horizontal sectional view through a dent taken substantially on the line 5—5 of Figure 2; and

Figure 6 is a fragmentary horizontal sectional view taken substantially on the line 6—6 of Figure 2.

Referring to the drawings, it will be seen that the form of reed illustrated comprises 85 a rack or base bar 11, dents 10 and a retaining wire 18.

The dents 10 are rigidly secured in spaced slots in the rack or base bar 11 in any suitable manner, as by soldering. Each dent 90 consists of a single straight bar, the middle portion being rounded as viewed in cross section (see Fig. 4) and its end portions being substantially rectangular. As shown in Figure 5, the lower end portion is rectangular or otherwise shaped to snugly fit the slots in the rack or base bar 11. The upper end portion is substantially rectangular except that the bar is widened in any suitable manner in order to further restrict the space 100 between the adjacent dents. In the form of the invention shown, this is accomplished by slitting vertically the front of the upper end of the dent as shown at 14 in Figure 3. It is to be understood, however, that the 105 result might be accomplished in other ways.

This construction of reeds lends itself to accurate quantity production. Furthermore, the warp threads may be crossed to form the shed without injuring or breaking 110

the yarn, the rounded intermediate portions of the dents presenting no sharp edges. The restricted spaces between the upper end portions of adjacent dents hold the threads 5 against lateral displacement so that the filling about the tufts and within the warp threads may be beaten up efficiently.

Two or more of the dents, preferably all of them, at their upper rear corners are provided with integral ears 16, as shown in Figure 2. These ears are provided with apertures 17 for the retaining wire 18. It will be noted that the retaining wire 18 is supported so that the warp threads may approach nearer to the top of the reed than heretofore. Furthermore, the upper front corner 18^a of each dent is at a lower elevation than the top of the ear. As a result, the path 19 of the knife, at the front of the reed, 20 is closer to the warp threads than with prior constructions. In this structure a plane tangent to the top of the ear and the upper front corner of the dent is inclined forwardly. Furthermore, a plane tangent to 25 the top of the retaining wire 18 and the front corner of the dent is substantially horizontal. Expressed in still another way, the vertical distance between a horizontal plane tangent to the under side of the retaining wire 18, on the one hand, and a horizontal plane tangent to the upper front corner of 30 a dent is less than heretofore.

With this form and arrangement of parts it is clear that the warp threads can be raised 35 to a plane much nearer to the path of the knife than heretofore, with the result that the pile may be cut closer to the ground fabric, and moreover this result has been secured without decreasing the vertical travel 40 of the warp threads. Indeed these threads, in the present invention, have a maximum vertical travel while still retained in the reed.

Although the invention has been described 45 in detail, it is to be understood that it is not thus limited but includes modifications and changes which come within the scope of the appended claims.

Having thus described my invention, what 50 is claimed as new and desired to be secured by U. S. Letters Patent is:

1. A reed for pile fabric looms, including in combination, a plurality of dents, at least two of said dents each having an ear at the upper rear corner thereof and means carried by said ears for retaining warp threads in the reed.

2. A reed for pile fabric looms, including in combination, a plurality of dents, at least 55 two of said dents having a rearwardly extending ear at the upper rear corner thereof, the top surfaces of said ears being disposed above the upper front corner of said dent, and means carried by said ears for retaining 60 warp threads in the reed.

3. A reed for pile fabric looms, including in combination, a plurality of dents, the upper front portion of each dent being widened laterally, thereby constructing the spaces between adjacent dents, at least two 70 of said dents each having an ear at the upper rear corner thereof, and means carried by said ears for retaining warp threads in the reed.

4. A reed for pile fabric looms, including in combination, a plurality of dents, the upper front portion of each dent being widened laterally, thereby constricting the spaces between adjacent dents, at least two of said 80 dents each having an ear at the upper rear corner thereof, and means carried by said ears for retaining warp threads in the reed, a plane tangent to the top of said means and the front corners of the dents being substantially horizontal.

5. A reed for pile fabric looms, including in combination, a plurality of dents and means adjacent the rear upper corner of each dent for retaining the warp threads in the reed, said means being located substantially as high as the upper front corners of the dents.

6. A reed for pile fabric looms, including in combination, a plurality of dents, a slotted rack for supporting said dents, each dent at its lower end having a rectangular portion adapted to fit into the slots of said rack and at its upper end a substantially rectangular portion widened laterally at its front face, whereby the space between adjacent dents is wider at the lower than the upper ends of the dents.

7. A reed for pile fabric looms, including in combination, a plurality of dents, a slotted rack for supporting and spacing the lower ends of said dents, each dent consisting of a single straight bar of solid cross section, its lower end portion being of rectangular cross section and adapted to fit into the slots of said rack, its upper end portion being of substantially rectangular cross section and widened laterally for constricting the space between the upper ends of adjacent dents, the portion of the dent intermediate said end portions having a rounded outline as viewed in cross section, an apertured ear at the rear upper corner of each dent, and a wire passing through said ears and extending across the back of said reed for preventing warp threads from rising 100 above the upper ends of said dents.

8. A reed for pile fabric looms, including in combination, a plurality of dents, a slotted rack for supporting and spacing the lower ends of said dents, each dent consisting of a single straight bar of solid cross section, its lower end portion being shaped to fit into the slots of said rack, and its upper end portion being formed to provide a restricted space between adjacent dents, an 115

apertured ear at the upper rear corner of said dents, and a wire supported in the apertures of said ears and extending across the back of the reed, for preventing the warp threads from rising above the upper ends of said dents.

9. As an article of manufacture, a dent for pile fabric looms, consisting of a single straight bar of solid cross section having its lower end portion of rectangular

cross section, its upper end portion of substantially rectangular cross section, the front face thereof being wider than the rear face, the portion of the dent intermediate said end portions having a rounded outline as viewed in cross section, and an apertured ear at the rear upper corner of said dent.

In testimony whereof I hereunto affix my signature.

GEORGE CROSSLAND.
